ELECTRICAL CONNECTOR

Edward S. Miller, Los Angeles, Calif.

Application August 10, 1950, Serial No. 178,701

8 Claims. (Cl. 174—88)

1

This invention relates to a connector of the type employed for electrically connecting adjacent ends of conductors.

The primary object of the invention is to connect adjacent ends of conductors and effect good electrical conductivity between said conductors.

Another object is to frictionally engage the conductors with a connector of conducting material so as to assure good electrical contact between the conductors and the connector.

A further object is to automatically advance the connector into contact with the conductors as the parts are moved into assembled relation.

The above and other objects may be attained by employing this invention which embodies among its features a tubular body having an inclined inner wall, a tongue adapted to enter said tubular body and having an inclined face which corresponds in inclination to that of the inclined wall, said tongue having longitudinal conductor receiving grooves opening through the inclined face thereof and a staple of conducting material having the legs thereof disposed in each groove and adapted to be engaged by the inclined wall to force the legs of said staple into good electrical contact with conductors lying in the grooves as the tongue is entered into the tubular body.

In the drawings:

Figure 1 is a longitudinal sectional view through a connector embodying the features of this invention, showing the tongue partially entered into the tubular body thereof.

Figure 2 is a view similar to Figure 1 illustrating the device completely assembled.

Figure 3 is a horizontal sectional view taken substantially along the line 3—3 of Figure 2.

Figure 4 is a transverse sectional view taken substantially along the line 4—4 of Figure 2.

Figure 5 is a plan view of the tongue forming one of the elements of the connector, and

Figure 6 is a perspective view of a connecting staple of the type employed for effecting good electrical contact with conductors.

Referring to the drawings in detail a tubular body 10 is provided at one end with an end closure 12 and at its opposite end with a socket 14. Extending radially through the tubular body and communicating with the socket 14 is an opening 16 the purpose of which will hereinafter appear. Extending longitudinally within the tubular body between the socket 14 and the end closure 12 is a flat oblique wall 18 which extends at an angle away from the longitudinal axis of the tubular body as it extends from the end closure 12 and

2

toward the socket 14. Formed in the end closure 12 is a longitudinal passage or opening 20 for the reception of a cable 22 carrying electrical conductors 24 and 26. The opening 20 opens into the interior of the tubular body 10 and the conductors 24 and 26 are extended into the tubular body as will be readily understood upon reference to the drawings.

A tongue 28 having an inclined wall 30 which inclines longitudinally and corresponds in angular disposition to the inclination of the inclined wall 18, is adapted to be entered into the body through the socket 14, as suggested in the drawings. The upper face 30 of the tongue 28 is provided with spaced longitudinally extending parallel grooves 32 and 34 for the reception of the conductors 24 and 26 respectively. Carried by the tongue 28 at the thicker end thereof is a head 36 having an axial opening 38 extending therethrough for the reception of a cable 40 carrying conductors 42 and 44 which, as illustrated in the drawings, extend into the grooves 32 and 34 respectively in substantial alignment with the conductors 24 and 26 which lie in the grooves. The head 36 is provided with a radial screw threaded socket 46 which when the parts are fully assembled aligns with the opening 16 for the reception of a suitable fastener 48 such as a machine screw.

Formed in the bottom of the groove 32 intermediate the ends thereof and adjacent opposite sides of said groove are longitudinally spaced sockets 50 and 52 and similar recesses 54 and 56 are formed in the bottom of the groove 34 intermediate the ends and in opposite side walls of the groove 34. The upper ends of sockets 50 and 52 open into grooves 58 and 60 formed in opposite side walls of the groove 32. Likewise the upper ends of the sockets 54 open into grooves 62 formed in opposite side walls of the groove 34 while the upper ends of the sockets 56 open into grooves 64 formed in opposite side walls of the groove 34. The grooves 58, 60, 62 and 64 lie perpendicular to the bottoms of the grooves 32 and 34 respectively and form guides for the prongs of a pronged fastener designated generally 66. This pronged fastener comprises a flat plate body portion 68 formed of conducting material from opposite ends of which project spaced legs or prongs 70 and 72. As illustrated the legs 70 and 72 project from one end of the body 68 in parallel relation and increase in width as they approach the body 68 to form substantially V-shaped recesses in which the adjacent ends of the conductors in one of the grooves 32 or 34

are received. In the preferred form of the invention the adjacent edges 14 of the prongs 10 are inclined to form sharpened edges 16 while the adjacent edges 18 of the prongs 12 are inclined to form sharpened edges 20. It will thus be seen that as a pronged fastener 66 is advanced into one of the grooves 32 or 34 in which conductors are located the sharpened edges 16 and 20 will bite into the surfaces of the conductors to effect good electrical contact therewith.

In use a cable 22 is passed through the opening 20 in the end closure 12 of the tubular body 10 and the insulated conductors 24 and 26 in said cable are separated so as to extend into the interior of the tubular body 10. The inner ends of the conductors 24 and 26 are bared for a short distance so that they may be exposed for electrical connection to the bared ends of the conductors 42 and 44 of a cable 40 which is passed through the opening 38 in the head 36 of the tongue 28. As illustrated in the drawings the insulated conductors 42 and 44 of the cable 40 lie in the grooves 32 and 34 respectively of the tongue 28 with their bared ends projecting slightly beyond the grooves 58 and 62 in the walls of the grooves 32 and 34 respectively. A pronged fastener such as is illustrated in Figure 6 is then disposed in bridging relation with each groove so that the prongs thereof lie in the grooves 58, 60, 62 and 64. With the parts in this position, the tongue 28 is advanced into the tubular body 10 so that the angular wall 18 thereof will engage the bodies 68 of the pronged fasteners 66 and move the prongs thereof through their respective grooves toward the sockets 50, 52, 54 and 56. As the parts are pushed together, the bared ends of the conductors 24 and 26 will be entered between the legs of the fasteners 66 remote from the conductors 42 and 44 so that by the time the fasteners are advanced so that the ends of the legs thereof remote from the body 68 thereof enter the sockets in the bottoms of the grooves 32 and 34, the sharpened edges of the prongs will bite into the bared ends of the conductors 24, 26, 42 and 44 so as to form good electrical contact with said conductors. Since the body portion 68 and the prongs 10 and 12 of the pronged fasteners 66 are formed of electrically conductive material, it will be evident that good electrical contact will be established between the conductors 24 and 42 and between the conductors 26 and 44. As the parts are pushed together, the opening 16 will align with the threaded recess 46 so that the fastener 48 may be entered into the recess through the opening 16 to hold the parts against separation.

It will be understood of course that the tubular body 10 and the tongue 28 are to be formed of a non-conducting material such as plastic, rubber or the like.

While in the foregoing there has been shown and described the preferred form of this invention, it is to be understood that minor changes in the details of construction, combination and arrangement of parts may be resorted to without departing from the spirit and scope of the invention as claimed.

I claim:

1. In a connector for electrically connecting adjacent ends of conductors, an elongate tubular body having an inner longitudinal wall extending oblique to the length thereof, a tongue adapted to enter one end of said tubular body, said tongue having a longitudinal inclined face that corresponds to the angular disposition of said oblique

wall, the inclined face of the tongue having a longitudinal conductor receiving groove therein, and a pronged staple of conducting material lying across and in straddling relation with the groove with its prongs entering the groove, said staple having a surface positioned to be engaged by the inclined wall and forced into contact with conductors lying in the groove as the tongue enters the tubular body.

2. In a connector for electrically connecting adjacent ends of conductors, an elongate tubular body having an inner longitudinal wall extending oblique to the length thereof, a tongue adapted to enter one end of said tubular body, said tongue having a longitudinal inclined face that corresponds to the angular disposition of said oblique wall, the inclined face of the tongue having a longitudinal conductor receiving groove therein, a pronged staple of conducting material lying across and in straddling relation with the groove with its prongs entering the groove, said staple having a surface positioned to be engaged by the inclined wall and forced into contact with conductors lying in the groove as the tongue enters the tubular body, and means carried by the tubular body and by the tongue to receive a fastener by which the tongue is held in said body.

3. In a connector for electrically connecting adjacent ends of conductors, an elongate tubular body having an inner longitudinal wall extending oblique to the length thereof, a tongue adapted to enter one end of said tubular body, said tongue having a longitudinal inclined face that corresponds to the angular disposition of said oblique wall, the inclined face of the tongue having a longitudinal conductor receiving groove therein, a pronged staple of conducting material lying across and in straddling relation with the groove with its prongs entering the groove, said staple having a surface positioned to be engaged by the inclined wall and forced into contact with conductors lying in the groove as the tongue enters the tubular body, a head on the tongue for entrance into the tubular body, said head having a radial screw threaded recess therein, said tubular body having a radial opening extending therethrough, and a fastening screw entering the recess through said opening.

4. In a connector for electrically connecting adjacent ends of conductors, an elongate tubular body having an inner longitudinal wall extending oblique to the length thereof, a tongue adapted to enter one end of said tubular body, said tongue having a longitudinal inclined face that corresponds to the angular disposition of said oblique wall, the inclined face of the tongue having two spaced parallel longitudinal conductor receiving grooves therein, and pronged staples of conducting material lying across and in straddling relation with each groove with the prongs thereof entering their respective grooves, said staples each having a surface positioned to be engaged by the inclined wall and forced into contact with conductors lying in said grooves by the tongue as the tongue enters the tubular body.

5. The invention according to claim 1, wherein said staple comprises spaced V portions, each of which portions receives a conductor.

6. A connector for electrically coupling ends of two electric current conductors, comprising an elongate body having a longitudinal chamber opening through one end, the opposite end of the body having an axial passage for the extension of a conductor end into the chamber, said chamber having one longitudinal wall flat and

extending at an angle oblique to the length of the chamber, a tongue adapted to be inserted into the chamber through said one end and having a longitudinal surface disposed at an angle to the length of the tongue corresponding to the angle of said wall, said wall and tongue surfaces being in opposed relation in the assembled connector, a groove in and extending longitudinally of the length of the tongue surface to receive ends of two conductors, and a coupling conductor for 10 electrically connecting said ends comprising a plate disposed longitudinally of and bridging the groove and having leg members projecting into the groove each in crossed contacting relation with a conductor end, said chamber wall functioning in the insertion of the tongue into the chamber to press against said plate to force said legs into conductor engaging position.

7. The invention according to claim 6, wherein said leg members are arranged to provide two V 20 slots opening downwardly into the tongue groove

and into each of which an end of the conductor is engaged.

5 8. The invention according to claim 7, wherein said tongue groove has opposite wall faces provided with transverse grooves for slidably receiving edges of the leg members to maintain said coupling conductor against movement longitudinally of the tongue.
